UNITED STATES PATENT OFFICE.

EMIL K. F. STREICHERT, OF DETROIT, MICHIGAN.

RADIATOR.

1,189,506.

Specification of Letters Patent.

Patented July 4, 1916.

Application filed January 14, 1914. Serial No. 812,058.

To all whom it may concern:

Be it known that I, EMIL K. F. STREICHERT, a citizen of the United States of America, residing at Detroit, in the county 5 of Wayne and State of Michigan, have invented certain new and useful Improvements in Radiators, of which the following is a specification, reference being had thereto in the accompanying drawings.

10 This invention relates to radiators or water cooling devices for automobiles and to an arrangement thereof which combines simplicity of construction with great effectiveness because of the position of the cooling elements and the few seams or joints required.

The invention consists in the matters hereinafter set forth and more particularly pointed out in the appended claim.

20 In the drawings, Figure 1 is a view in end elevation, partially broken away of a radiator that embodies features of the invention; Fig. 2 is a view in detail in vertical section through a portion of the cooling 25 section; Fig. 3 is a view in transverse section through a portion of the cooling section; and Fig. 4 is a view in detail of a spacing plate.

Referring to the drawing a frame 1 of 30 suitable design and material has an upper water space 2 or supply tank and a lower water space or tank indicated at 3, these parts being in communication through upright water spaces formed by a cooling section 35 whose general conformation is indicated diagrammatically at 4. The latter which is of the honeycomb type is formed of plates arranged in pairs and extending from the upper member 2 to the lower member 3. One of the plates 6 of each pair is 40 corrugated transversely, the corrugations being angular and preferably sharply defined. The companion plate 7 is likewise corrugated and is also provided with spacing ribs 8 that extend from the outer convex 45 part or crest of each corrugation to the adjoining plate 6 of a companion pair, the spacing ribs resting in the concave angles of said plate 6. The spacing ribs are formed 50 by folding the plate upon itself so that

lateral off-sets are obtained. These may be completely closed or may be slightly opened if desired. The plates of each pair are held in spaced relation so as to form sinuous water passages by the margins 9 and 10 55 thereof which are slightly inset toward each other and when completed are sweat soldered or intimately connected together to form a close joint.

One result of the construction is the fewness of joints as there are no seams to be closed save along the lateral margins of the plates and at the insertion thereof of the plates into the upper and lower water spaces. The spacing ribs are an integral 65 part of one of the plates and therefore there is no leakage possible in any connection between the ribs and the plate. Because of the sinuous paths traversed by the water the area exposed to the cooling effect of the air is considerable greater than if the passages were straight from top to bottom.

Obviously, changes in the details of construction may be made without departing from the spirit of my invention and I do 70 not care to limit myself to any particular form or arrangement of parts.

What I claim is:—

In a radiator, a honeycomb cooling section comprising pairs of spaced plates having off-set margins permanently secured together; one of said plates being corrugated, a rib formed at the crest of each corrugation, the other of said plates being continuously corrugated and free of ribs with the projecting ribs received in the depressions thereof and the crests of the corrugations being directed toward and spaced from the depressions in the first-named plate, the ribs of each pair of plates being arranged in alinement 80 and all pointing in the same direction and presenting cells having parallel end walls and angular side walls.

In testimony whereof I affix my signature in presence of two witnesses.

EMIL K. F. STREICHERT.
